BURIAL VAULT

Filed April 14, 1928

Frank Bartlow
INVENTOR

BY *Victor J. Evans*

WITNESS

UNITED STATES PATENT OFFICE

FRANK BARTLOW, OF MILLVILLE, PENNSYLVANIA

BURIAL VAULT

Application filed April 14, 1928. Serial No. 270,091.

My present invention has reference to a concrete burial vault and my primary object is the provision of a vault for this purpose in which the bottom is cast separate from the body and is of such construction that, when arranged in the ground the same will have a locking engagement with said surface, regardless of the softness or irregularities thereof and further wherein the engagement between the body and the bottom is such that the body will not inflict undue strain against the bottom regardless of the condition of the ground in which the vault is arranged so that liability of injury to either the bottom or the body will be effectively prevented.

A further object is the provision of a vault for this purpose that shall be of reinforced concrete and of a type and construction to effectively preserve the casket arranged therein.

To the attainment of the foregoing the invention consists in the improvement as hereinafter described and definitely claimed.

In the drawings:

Figure 1 is a top plan view of a concrete burial vault in accordance with this invention.

Figure 2 is a sectional view approximately on the line 2—2 of Figure 1.

Figure 3 is a transverse sectional view approximately on the line 3—3 of Figure 1.

Referring now to the drawings in detail, the numeral 1 designates the base or bottom of the vault. The base is formed of a slab of concrete or like plastic material which is reinforced, as at 2. The base on its face at a suitable distance from its ends and edges is depressed, as at 3, thus forming the outer ends and edges of the base with a continuous rib 4 and the inner face of this rib is struck at an angle as indicated by the numeral 5. The upper corner of the base is also struck at an angle, as at 6, and this angle edge is continuous around the base.

The hollow body of the improvement is indicated by the numeral 7. This body is also formed of reinforced concrete and has its top 8 arched. The body 7 is reinforced, as at 9, and the arched top 8 of the body is cen-

trally thickened, as at 10, to strengthen the said top. Of course, the top may be thickened throughout the length thereof.

The lower sides and edges of the body 7 are formed with outwardly extending portions 11 and the outer faces of these projected portions are covered by metal plates 12 whose flanged edges 13 are let in the said part 11 of the body. The inner edge, adjacent to the outer end of the body, is formed with a continuous recess 14 that is provided with an upper angle wall 15, and this angle wall 15 is designed for coengagement with the angle corner 6 of the base 1.

The ends of the body 7, adjacent to the top 8 thereof are molded to provide the same with outwardly extending downwardly directed handle portions 16, and the under faces of these handle portions are grooved, as at 17.

The base, of course, is first received in the grave and rests on the bottom thereof. The earth surface in the bottom of the grave will be received in the depression 3 and will contact with the shoulder 5 and be likewise contacted by the continuous projection 4. After the casket is arranged on the base the body is lowered thereover. If desired a suitable sealing cement may be arranged between the confronting edges of the base and the body. The comparatively thick but widened portions 11 at the outer edges of the body, and the metal reinforcements 12 thereon, contacting with the ground surface will protect the base 1 from undue pressure by the body.

The thickened and, therefore, reinforced arched portion 10 of the body will effectively protect the same from the earth which is arranged thereon and will likewise direct the earth from the said top along the sides of the body.

The construction and advantages of the improvement will, it is thought, be understood by those skilled in the art without further detailed description.

Having described the invention, I claim:

A reinforced plastic burial vault, including a base and a body to be arranged over to cover and to enclose the base, said base com-

prising a slab having its outer face depressed to form the same with a continuous rib at the outer corners thereof and the inner edges at the corners of the base struck at an angle, the body having its inner face and its lower edges formed with a continuous depression and the upper wall provided thereby being arranged at an angle to contact with the angle corner edges of the base slab when the body is arranged over the base slab, said body being thickened outwardly around the depressed portion thereof, and one of the reinforcements of the body being extended transversely below the outer edge of the thickened portion.

18. In testimony whereof I affix my signature.
FRANK BARTLOW.
